UNITED STATES PATENT OFFICE.

JAMES M. MORRISON, OF SIOUX CITY, IOWA.

EXPLOSIVE-ENGINE.

No. 821,370.

Specification of Letters Patent.

Patented May 22, 1906.

Application filed December 30, 1904. Serial No. 238,988.

To all whom it may concern:

Be it known that I, JAMES M. MORRISON, a citizen of the United States, residing at Sioux City, in the county of Woodbury and State of Iowa, have invented certain new and useful Improvements in Explosive-Engines, of which the following is a specification.

My invention relates to explosive-engines, and while particularly adaptable for use in connection with explosive-engines of the four-cycle order may by minor modifications be applied to two-cycle engines.

It is well known that in the ordinary explosive-engine the explosion is produced while the piston is at its extreme inward limit and while the crank is on the dead-center. It will be readily understood that where the explosion occurs with the crank so centered the force of the explosion is wasted in a useless and undesirable pressure exerted upon the driving-shaft. To overcome the waste of the expansive pressure of the exploded gas, engines have been constructed wherein the explosion is timed to occur after the crank has passed its center and after the piston has begun its outward stroke. It will be readily seen that the outward movement of the piston thus enlarges the explosion-chamber and that the power required to compress the gas preparatory to explosion is to some extent wasted by the expansion permitted by the enlargement of the explosion-chamber.

The object of my invention is to produce an explosive-engine wherein the explosion occurs after the crank has passed its center and after the piston has begun its outward stroke, but with the explosion-chamber at its minimum capacity.

A further object of my invention is to provide an explosive-engine having a movable cylinder-head mounted within the cylinder and which moves in conjunction with and at a short distance from the piston while the piston is finishing its inward and beginning its outward stroke, thus confining the compressed fuel within a minimum space until the time of explosion, after which the cylinder-head remains stationary until the return of the piston.

With these and other objects in view the present invention consists in the combination and arrangement of parts, as will be hereinafter more fully described, shown in the accompanying drawings, and particularly pointed out in the appended claims, it being understood that changes in the form,

proportion, size, and minor details may be made within the scope of the claims without departing from the spirit or sacrificing any of the advantages of the invention

On the drawings, Figure 1 is a side view of my improved explosive-engine, showing in vertical section the parts as they are disposed at the moment of explosion. Fig. 2 is a vertical sectional view of the cylinder and working parts of my improved engine with the piston at its extreme outer limit. Fig. 3 is a view in vertical section of the working parts of my explosive-engine, showing the piston at its extreme inner limit.

Like characters of reference designate corresponding parts throughout the several views.

In its preferred embodiment my improved explosive-engine consists of a cylinder 1, mounted in any approved manner, as upon the base 2, and having a piston 3, mounted to reciprocate therein. A driving-shaft 4 is conveniently mounted upon the base, and a crank 5, rigidly secured thereto, is connected with the piston 3 by the link 6. The cylinder 3 is provided with any approved ports 7, the valve of which may be operated in any approved manner, as by cams 8, mounted upon rotating shaft 9. Within the cylinder 1 is also mounted a reciprocating cylinder-head 10, having a rod 11 rigidly secured thereto and extending without the cylinder, preferably coincident with the axis thereof. The rod 11 may be slidably mounted in any approved manner, as in the bearings 12. Secured to the shaft 11 is a collar 13, carrying a pintle 14, which may be provided at its end with a cam-roller 15. A cam-disk 16, provided with a cam-slot 17, may be rotatably mounted adjacent the rod 11, with the cam-roller 15 disposed within the cam-slot 17. The cam-disk 16 may be given a rotary motion in any approved manner, as by means of the gears 18 and 19, receiving motion from the rotating shaft 9, which operates the valves of the ports 7. In a four-cycle engine the shaft 9 would of necessity be geared to rotate once at each two revolutions of the driving-shaft 4, and if the cam-disk 16 is operated from the said shaft the gears 18 and 19 may be proportioned two to one, as shown, to rotate the cam-disk once for each revolution of the driving-shaft.

The operation of my improved explosive-engine is as follows: With the parts disposed as shown in Fig. 1 the explosion is timed to

occur between the piston 3 and the movable cylinder-head 10. The explosion causes an outward movement of the piston 3 to its extreme outer limit, as shown in Fig. 2. While 5 the piston 3 is moving outward, the cam-disk 16 is rotating in the direction indicated by the arrow, and the slot 17, formed as shown, holds the cylinder-head stationary during such outward movement and while the 10 crank-pin is traversing the arc in the direction indicated by the arrow from the point B to the point A. When the crank-pin reaches the point B, the disk 16 has rotated, so that a further rotation thereof causes the 15 cam-roller 15 to follow the angularly-disposed portion of the slot 17 and to move the cylinder-head 10 through the space C D. The angular portion of slot 17 is so proportioned and disposed that the movement C D 20 of the cylinder-head 10 is equal to and simultaneous with the movement of the crank-pin from B to A and through the horizontal distance E F, which is equal to the distance C D, so that from the position of the piston 3 25 with the crank-pin at B the piston-head 10 moves simultaneously with and at an unvarying distance from the piston 3 until the crank-pin again reaches the point A. It will thus be seen that the cylinder-head 10 moves simultaneously with the piston 3 at each stroke thereof while the said piston is finishing its inward and beginning its outward stroke, so that for the purpose of exhausting and 30 scavenging the movable piston-head 10 serves all the utility of the stationary head.

While I have shown and described a rotating cam-disk for operating the movable piston-head, it is obvious that the said head may be operated by other means or mechan-

ical equivalents. It is also obvious that if 40 the rotating disk is used the rotary motion may be obtained from a source other than the rotating shaft which operates the port-valve and that other changes in the form, manner of operation, and minor detail may 45 be made without departing from the spirit of my invention or the scope of the claim.

Having thus described my invention, what I claim as novel, and desire to secure by Letters Patent, is—

An explosive-engine comprising a cylinder, a piston mounted to reciprocate within the cylinder, a rotating crank-arm, a link connecting the piston and the crank-arm, a cylinder-head mounted to reciprocate within the cylinder, an outwardly-extending rod secured to said cylinder-head, a cam-disk disposed for coöperation with the rod, connecting means whereby the rotation of the crank-arm produces a rotary movement of 60 the disk which in turn produces an intermittent reciprocating movement of the cylinder-head in coöperation with and at a short distance from the piston while the piston is finishing its inward and beginning its outward stroke and means for producing the explosion after the piston has begun its outward stroke and after the crank-arm has passed the center and while the distance between the piston and the cylinder-head is at 65 its minimum.

In testimony whereof I affix my signature in presence of two witnesses.

JAMES M. MORRISON.
